UNITED STATES PATENT OFFICE.

MEREDITH LEITCH, OF POUGHKEEPSIE, NEW YORK, ASSIGNOR TO THE DE LAVAL SEPARATOR COMPANY, OF NEW YORK, N. Y., A CORPORATION OF NEW JERSEY.

DRIVING MEANS FOR CENTRIFUGAL BOWLS.

1,373,085.

Specification of Letters Patent. Patented Mar. 29, 1921.

Application filed June 6, 1919. Serial No. 302,089.

To all whom it may concern:

Be it known that I, MEREDITH LEITCH, a citizen of the United States, residing at Poughkeepsie, county of Dutchess, and State 5 of New York, have invented a new and useful Improvement in Driving Means for Centrifugal Bowls, of which the following is a full, clear, and exact description, reference being had to the accompanying drawings, 10 which form a part of this specification.

My invention is an improvement in means for mounting centrifugal bowls on, and driving them by, the spindles of their machines.

15 My object is to provide a mounting and driving means in which there is no tendency to cause eccentricity or misalignment of the bowl with the spindle and yet in which there will always be a sufficient driving force.

20 In my patent application filed April 30, 1919, Serial No. 239,640, I set forth a bowl drive which depends entirely on the friction between a taper cone of a non-seizing angle on the spindle and a socket of a similar angle 25 in the bowl. This for many conditions is sufficient. However, it is desirable, in order to insure against seizing, that the broadest possible angle of taper be given to the spindle and socket and, in some cases of light 30 weight bowls having a large capacity, there may not be friction enough to drive the bowl with liquid flowing through it. With such bowls I make use of the auxiliary driving means described in the present invention.

35 In the accompanying drawings, which illustrate a preferred embodiment of my invention,—

Figure 1 is an elevation, partly in section, of a centrifugal bowl, the upper portion of 40 the spindle on which it is mounted, and the driving means between them.

Fig. 2 is a vertical section of the upper portion of the spindle, the part of the bowl in immediate contact therewith, and the 45 driving means.

Fig. 3 is a cross-section on the line 3—3 of Fig. 2.

Fig. 4 is a cross-section, on a still larger scale, of the spindle alone.

50 *a* is a bowl spindle having a tapered upper end and supported and driven in the usual manner by bearings and gearing not shown. *b*, *b*, are weights of lead or other soft heavy

material in cavities provided in the upper part of the spindle. *c*, *c*, are retaining rivets extending through holes in the spindle and having heads *d* underneath which the material of the weights extends and surrounds the necks *e*. From the bottom of the bowl *f* extends upward a hollow shaft *g*, 60 provided with a bushing *h* closely fitting the spindle *a*. In the upper end of the bushing *h* is secured a plug *i* having a taper socket adapted to fit the taper end of the spindle *a*. Underneath each of the heads *d* of the rivets 65 *c* is a clearance space *j* which permits a slight outward movement of the weights.

In the manufacture of the described centrifugally engageable clutch, I prefer to proceed by cutting out the cavities, boring the 70 rivet holes between opposite cavities, placing the rivets *c* centrally in the holes, casting the weights *b* in the cavities, around the rivets and under their heads, and then forcing the rivets longitudinally a short distance first 75 toward one side and then toward the other, thereby compressing the metal under the heads and providing the described clearances to permit outward movement of the weights.

The most used method of driving a centrifugal bowl is by having a part of the top of the spindle cut away to form a member which, in combination with a mating member in the bowl, forms a positive clutch. This has two serious faults. When the bowl 85 is placed on the spindle, it must be carefully turned around until the clutch engages, and after engagement the jaws, or equivalent, of the clutch have, because of unavoidable slight irregularities in manufacture, a tendency 90 to throw the bowl out of concentricity with the spindle, causing rough running.

I know that it is old to drive centrifugal bowls by centrifugal clutches. All clutches 95 previously made for this purpose have been of such large size as to make necessary an increased distance between the top bearing of the spindle and the bottom of the bowl. The movable parts at large diameter are 100 also liable to have unequal radial movements and consequently throw the whole revolving mass out of balance. I know, also, that it is old to support a centrifugal bowl on a taper or conically ended spindle, but when 105 this taper is made so blunt that the bowl can

be easily removed, there is danger that the bowl will slip when the greatest power is required.

In my improved construction I provide a spindle having at its top a portion with a taper blunt enough to insure easy removal of the bowl but still acute enough to insure the friction required to gradually bring the empty bowl up to speed, and below the taper portion a cylindrical portion having centrifugally engageable friction members normally entirely within the cylindrical portion. I provide the bowl with a cylindrical bushing closely fitting the cylindrical portion of the spindle and having at its upper end a plug with a taper socket to fit the taper portion of the spindles.

In operation, the bowl is placed on the spindle, in any rotational position, and the machine started. The friction of the taper portion will gradually start the bowl. As the speed of the spindle increases the weights *b, b*, will press outward against the bushing *h* and cause a friction that will greatly increase the driving force. Because the outside surfaces of the weights form part of the cylindrical surface of the spindle and because the bushing *h* closely fits the spindle, the actual movement of the weights is so small as to have no effect on the balance of the device. Because the weights are entirely within the normal diameter of the spindle and are inside the bowl, the device interferes in no way with placing the top bearing close to the bowl.

Having now fully described my invention, what I claim and desire to protect by Letters Patent is:

1. In driving means for centrifugal bowls, the combination with the supporting and driving spindle having clutch receiving cavities, of a bowl having a cylindrical spindle receiving socket adapted to inclose said cavities and spindle and closely fit the spindle along that part of the length thereof in which the cavities are formed, and a centrifugally operable friction clutch normally entirely within the spindle and radially movable to frictionally engage the surrounding wall of the socket.

2. In driving means for centrifugal bowls, the combination with the bowl, of a supporting and driving spindle, means to frictionally drive the bowl from the spindle, and an independent centrifugally operable friction member carried by the spindle and adapted, as the speed of rotation of the bowl increases, to move into frictional driving engagement with the bowl.

3. Driving means for centrifugal bowls comprising a spindle having a friction cone of a non-seizing angle and a centrifugally engageable friction clutch normally entirely within the spindle.

4. In driving means for centrifugal bowls, the combination with the bowl, of a supporting and driving spindle, said bowl and spindle having coaxing conical bearing surfaces by means of which the bowl is started to rotate with and on the axis of the spindle, and a centrifugally operable friction member adapted, as the speed of the spindle and bowl increases, to create a friction between the bowl and spindle and thereby substantially increase the driving force.

5. Driving means for centrifugal bowls comprising, in combination, a spindle having symmetrically located cavities, weights normally just filling said cavities, and weight retaining devices adapted to permit slight outward movement of the weights under centrifugal force.

6. In driving means for centrifugal bowls, the combination with a bowl having an axial spindle-receiving socket comprising a lower cylindrical portion and an upper conical portion, of a supporting and driving spindle having a cylindrical portion and a tapered portion adapted to substantially fit said socket, and centrifugally engageable friction members normally within the spindle but adapted, under centrifugal force, to press outward against the wall of the bowl socket.

7. In driving means for centrifugal bowls, the combination, with the bowl, of a supporting and driving spindle, said bowl and spindle having coaxing conical bearing faces by means of which the rotation of the bowl is started, and centrifugally operable members normally within the spindle but slightly movable radially under centrifugal force to create the friction required to continue the driving of the bowl under operative conditions at high speed.

8. In driving means for centrifugal bowls, the combination with a bowl having a hollow shaft, a bushing within the shaft, and a conically socketed plug closing the upper end of the bushing, of a spindle having a body and conical upper end adapted to closely fit said bushing and plug, and centrifugally engageable friction members carried by the spindle and entirely surroundable by said bushing.

In testimony of which invention, I have hereunto set my hand, at Poughkeepsie, N. Y., on this 29th day of May, 1919.

MEREDITH LEITCH.
